METHOD OF MANUFACTURING
STRAW HATS

Oscar Wiedeman, Fall River, Mass.

Application October 3, 1934, Serial No. 746,701

5 Claims. (Cl. 2—193)

This invention relates to methods of manufacturing straw hats, and particularly to improvements in the operations of blocking and pressing roughly formed hat blanks, particularly of the sailor type, to shape them to the desired style.

Heretofore it has been common to shape, block and press roughly formed straw hats, which I shall term hat blanks, in a number of operations, usually requiring a period of days for completion, the several operations including an extensive softening treatment, a subsequent stretching of the softened hat blank over a male block and pressing the hat onto the block with a hot iron, drying the hat blank for a number of hours after removing it from the block and finally pressing the hat into its final shape in a female heated mold into which the blocked hat is pressed by the application of pressure against the inside of the hat. It is the primary object of my invention to eliminate entirely the operations of blocking the hat by stretching the blank over a male wooden block, with the accompanying steps of extensive softening, ironing, drying etc., and to improve on the pressing operations in common use heretofore by providing a method in which the hat blank is completely blocked, pressed and shaped in a single operation of relatively few steps.

I have found that the preliminary blocking operation can be dispensed with and the hat blank can be completely blocked and shaped in the outer heated mold heretofore used to press the hat after blocking, if oversized hat blanks be used in the mold and if the blanks are properly positioned and treated in the mold.

Heretofore the blocking operation in which the softened straw hat blank is stretched over a male block, was considered essential or desirable to enable the operative to manipulate the convolutions of the braid and thereby to insure that the rows were even and properly distributed and that the edge of the braid forming the crown square, or juncture between the crown and tip, was properly positioned. I have found that the oversized hat blank, which is used in accordance with my method, readily distributes itself in the mold,—the surplus material resulting from the excess in size enabling the straw braids to fall into their proper position almost of their own accord. I thereby reduce the amount of manipulation of the braid required, which is obviously advantageous, and I have also found that whatever manipulation is required can be effectively performed from the inside of the hat and, as

will appear, my method provides for insuring the desired point alignment at the crown square by utilizing the lines of stitching, exposed on the inside of the hat, as a gauge to determine the position of the braid. It has been found that the elimination, by my method, of the initial blocking operation in which the hat is stretched into shape and the substitution therefor of a compressing shaping operation within the female mold, in which the hat is compressed to desired shape, greatly enhances the attractive appearance of the hat by eliminating the stretching of the braid fibres, and by condensing them to accentuate their fibre structure.

Any suitable apparatus can be employed in the performance of my novel method. A preferred apparatus is described in my co-pending application, Ser. No. 606,946, filed April 22, 1932, now Patent No. 2,010,285, of which the present application is a continuation in part.

One suitable apparatus is illustrated in the accompanying drawing, in which:

Fig. 1 is an elevation partly in section, showing the apparatus in working engagement; and—

Fig. 2 is a perspective view of the expansible shaping block forming a part of the apparatus.

The illustrated apparatus, which is described in more detail in my aforesaid Patent No. 2,010,285, comprises, in general, a lower pressing mechanism and an upper, vertically reciprocating pressing mechanism adapted to co-operate therewith.

The base 1 of the press supports a casting 2 adapted to house the lower pressing mechanism. The upper mechanism is supported by uprights 3 and 4, the upright 3 being journaled in the base, as indicated at 5. The upright 3 may be rotated to swing the connected upright 4 into the position shown in Fig. 1, in which said upright 4 is locked in the apertured extension 6 of the base, for example, by means of the nut 7 and hand lever 8.

The uprights 3 and 4 are joined by the reciprocating head 20, having at its extremities the bearings 21 and 22 adapted slidably to embrace the uprights 3 and 4. Vertical reciprocation of the head 20 and pressing mechanism carried thereby is effected in any convenient manner, for example, by toggles (not shown).

The casting 2 is hollowed out at 50 to form a steam chest suitably connected to a supply of steam for heating the lower pressing mechanism. The said mechanism comprises, in general, an outer mold shaped to receive the hat and an in-

ner expansible shaping block adapted to be placed within the hat when the hat is in position in the outer mold, to expand against the interior of the hat to effect the desired pressing operation. This expansibility of the inner block is derived from the construction of the block whereby portions of the same may be forced away from other portions and the outside dimensions of the thus separated block are increased.

10 The outer mold consists of a hollowed block 51, which is divided into two separable sections, both of which are received by the upper part of the casting 2 and thereby firmly secured together. The locking band 98 is provided as an 15 additional security against relative displacement of the sections of the block 51.

In Fig. 1 the numeral 60 indicates a straw hat in place for a pressing operation, at which time the hat is inserted in an inverted position, as indicated, with the tip 61 of the crown lowermost. The crown of a sailor straw hat is generally slightly tapered from the point of intersection of the brim and crown to a slightly broader section at the crown tip. It is because of this flaring formation of the hat crown that the mold 51 is divided into removable sections, enabling the operator to remove the hat after pressing.

The expansible shaping block indicated generally in Fig. 2, which is placed within the crown 30 of the hat after the hat is in place in the outer mold 51, comprises, as shown in detail in Fig. 2, a number of blocks 70 which are suitably shaped, as indicated, to conform to the above noted internal shape of the outer mold. The blocks 70 35 may be of hollow construction, as indicated in Fig. 1. After the block sections 70 are placed within the hat, the central expanding core, indicated generally as 71, is placed in the center of the blocks, as indicated in Fig. 2. The core 71 40 consists of a number of sections 72, generally triangular in cross-section, which are yieldingly held together by springs or other suitable means as known in the art. The assembled sections 72 are drilled in the center to form a tapered aperture 73, into which may be forced the plunger 74. The plunger 74 is integral with the threaded member 91, and is carried by the head 20 by 45 the screw threaded hollow in the member 92. By rotating the wheel 93, the member 91 is rotated and thus the plunger 74 may be raised or lowered.

In order that the thrust of the plunger 74 may not force the core 71 downwardly independently of the hollowed blocks 70, the inward face of each block 70 may be provided with a central vertically extending plate 101 having a vertical groove 97 open at its upper extremity and terminating in a shoulder 103 (Fig. 1). Projecting from each section 72 of the core 71 is a lug 96 adapted to be received by its corresponding groove 97 upon insertion of the core 71 centrally of the blocks 70 and to abut the shoulder 103 to prevent downward displacement of the core 71 independently of the sections 70.

The outer mold sections are provided with annular disc sections 81, which act as a form or templet to restrain distortion of the edge of the brim during the pressing operation and to ensure a brim of proper width and curvature.

The outer mold 51 is recessed at the upper 70 part of the mold face to receive a band 62 which, as indicated in Fig. 1, protrudes a slight distance above the plane of the mold brim face. This protruding band forms an elongated impression in the upper surface of the hat brim adjacent the juncture of the brim and crown.

As shown in Fig. 1, the upper surface 82 of the inner block sections 70 and the brim surface 83 of the outer mold 51 are substantially in the same plane when a hat is in place for the pressing operation. In order to force the inner shaping block downwardly to exert pressure against the crown tip 61 of the hat, I interpose the centrally perforated spacing member 84. This spacing member 84 is integral with the hollow threaded member 92 carried by the head 20 and the member 84 may be raised and lowered by rotating the same by means of the wheel 95.

The brim pressing plate 23 is adjustably supported by the reciprocating head 20 by means of the hollow screw threaded member 40, integral 15 with the brim plate and received by an internally screw threaded aperture 41 in the head 20. Adjustment of the vertical distance between the brim plate 23 and head 20 may thus be effected by rotation of the plate 23.

When the inner expansible shaping block (Fig. 2) is constructed of metal (for example, aluminum), the heat from the outer mold is readily communicated to this metal and is uniformly conducted throughout the shaping block, so that 25 heat is simultaneously applied to both the inner and outer surfaces of the hat blank.

To describe in detail the steps which comprise my novel method, the hat blank which has been sewed, stiffened with gelatin and thoroughly 30 dried in the usual manner is first softened to make the straw braids somewhat plastic, and I have found that the softening treatment comprising the initial step of my method may be much less thorough than that required under the old method wherein the hat is softened to the extent required to stretch it over the rigid wooden block in the blocking operation. Instead of soaking the hat in water and thereafter thoroughly steaming it, as has been common heretofore, I merely moisten the hat slightly by stroking it with a wet sponge and thereafter subjecting the hat to a brief steam treatment by exposing it to steam for a minute or so.

After the hat has been softened, the next step 45 in my method consists in initially shaping the hat by supporting the entire outer surface of the tip, crown and brim, and confining it to substantially the shape desired, simultaneously with the application of heat. This step is preferably 50 performed by inserting into a female mold of proper shape, for example, that shown in the accompanying drawing, a hat blank which is oversized. If it is desired to produce a hat which is size 7, for example, a size 7 outer mold is used 55 but a larger size hat blank is inserted in the mold, such, for example, as a size 7 1/4 or even 7 3/8 if the hat is of finer braid.

The oversized hat blank is inserted gently into the mold upside down, as has been common heretofore after the blocking operation, and it will be found that, as a result of the excess size of the blank, the semi-plastic condition of the braid and the heat of the mold, the braids will adjust themselves almost of their own accord to produce the desired evenly sloping convolutions of braid around the sides of the crown and in the surface of the tip, although some slight manipulation of the braid by the operative will sometimes be required to insure that each convolution 70 is in the exact position desired.

As is well known, it is essential that the row of points along the crown square be positioned in proper alignment with the edge of the crown square,—neither protruding over the edge nor 75

receding away from it. To obtain this proper alignment it has been customary heretofore to manipulate the braid at the crown square from the outside of the hat during the blocking operation, but as stated above my method provides for such alignment from the inside of the hat by utilizing the line of stitching which secures the row of braids in the tip nearest the crown square as a guide for determining the position of the points. After the hat has been inserted in the mold, the operative manipulates the row or rows of braid nearest the crown square to position the stitching in a line parallel to the line of the crown square and at a distance inwardly on the tip from the crown square which will position the points as desired. The proper spacing between the crown square and the line of stitching depends, of course, upon the distance inwardly from the points at which the braid is sewed, which may vary with shop practice. Approximately one quarter of an inch is usually the proper amount.

It is also essential that the so-called run-off, or line at which the row of braid in the tip adjacent the crown square crosses over the crown square to form the first row of the side of the crown, be disposed in the proper position at the back or side of the hat. This position can also be gauged by the stitching on the inside of the hat and it is essential that the operative guide the position of the run-off while inserting the hat in the mold.

The brim of the hat must be pressed and molded to the desired shape and my method provides that while the crown and tip are being molded in the female mold, the upper and lower surfaces of the brim are pressed to form a brim of proper thickness and the edge of the brim is molded to produce the desired smooth curvature. My method also provides that simultaneously with this brim pressing and molding operation the brim is impressed to form an elongated narrow groove around the edge of the brim adjacent the juncture of the brim and the crown, which is commonly provided to enhance the dressy appearance of the hat.

As disclosed in my prior co-pending application above-noted, and as illustrated in the accompanying drawing, the female mold into which the hat has now been inserted is provided with a flat pressing surface adapted to support and press one surface of the brim during the molding of the crown and tip and this pressing surface is provided with a molding plate adapted to abut the edge of the brim during the pressing of the surfaces thereof and, by resisting extrusion of the edge resulting from the pressure applied to the brim surfaces, to form a brim of proper width and of smooth edge curvature. The mold is also provided with a rib or projection disposed at the juncture of the brim and crown to form the above-noted groove.

After the hat has been inserted in the mold as described above, the brim is manipulated, if necessary, to insure that the edge of the brim is positioned within the edge molding plate and properly abuts the same.

After the hat has been positioned in the outer mold in the manner above described, the next step in my method comprises applying heat and pressure against the inside surfaces of the tip and crown, including the line of the crown square, and also to the surface of the brim opposite to that supported by the outer mold. Suitable apparatus for this purpose is illustrated in the accompanying drawing. Prior to the in-

sertion of the male mold into the hat, the mold may be heated in any desired manner to raise its temperature to approximately the temperature of the outer mold. The male mold, as illustrated, is provided with a top surface which abuts the inside surface of the tip of the hat, and side surfaces which abut the inside of the crown. A brim plate 23 abuts the surface of the brim opposite to that supported by the outer mold. After the heated male mold has been inserted in the hat and properly positioned it is expanded laterally and forced downwardly to apply the desired degree of pressure against the tip, crown and brim.

An important feature of my invention which should be noted in connection with the step of applying pressure to the inside surface of the hat is that the pressure-applying medium should preferably comprise a rigid body, rather than a yielding medium, such as the hydraulic pressure-applying mediums sometimes employed in the prior art, and furthermore that the degree of pressure applied be gauged by the compressed thickness of the straw braids rather than by the pounds per square inch of pressure applied. It will be apparent that as the inner and outer surfaces of the straw braid are confined between two rigid bodies, the braid can be molded and shaped properly by moving the rigid bodies together until a predetermined spacing equal to the desired thickness of the material has been reached, without crushing the braid.

It will be obvious that various details of my invention, the preferred form of which has now been described, may be varied without departing from the spirit of my invention which is to be limited only as indicated in the following claims.

I claim:

1. In the manufacture of straw hats, the method which comprises softening the hat blank by the application of moisture, initially confining the hat blank so moistened to substantially the external shape desired by supporting the outer surfaces of the tip and crown of the softened blank in a mold of a smaller size than that of the hat blank and thereafter applying pressure to the inner surface of the hat blank to mold the same to the desired shape.

2. In the manufacture of straw hats, the method which comprises softening the hat blank by the application of moisture, initially confining the hat blank so moistened to substantially the external shape desired by supporting the outer surfaces of the tip and crown of the softened blank in a mold of a smaller size than that of the hat blank, subsequently applying pressure to the inner surface of the hat blank by pressing against the inner surface with a rigid pressure-applying member and simultaneously applying heat to both the inner and outer surfaces of the hat blank to mold the same to the desired shape.

3. In the manufacture of straw hats, the method which comprises softening the hat blank by the application of moisture, initially confining the hat blank so moistened to substantially the external shape desired by supporting the outer surfaces of the tip and crown of the softened blank in a mold of a smaller size than that of the hat blank, subsequently applying pressure to the inner surface of the hat blank, applying heat to both the inner and outer surfaces of the hat blank, and applying pressure to both surfaces of the brim and simultaneously molding

the edge thereof by resisting extrusion of the edge resulting from the pressure so applied.

4. In the manufacture of straw hats, the method which comprises softening the hat blank by the application of moisture, initially confining the hat blank so moistened to substantially the external shape desired by supporting the outer surfaces of the tip and crown of the softened blank in a mold of the shape desired, subsequently applying pressure to the inner surface of the hat blank, applying pressure to both surfaces of the brim and simultaneously molding the edge thereof by resisting extrusion of the edge resulting from the pressure so applied, and
- 10 forming an elongated impression in the upper surface of the brim adjacent the juncture of the brim and crown.
- 15

5. In the manufacture of straw hats, the method which comprises softening the hat blank by the application of moisture, initially confining the hat blank so moistened to substantially the external shape desired by supporting the outer surfaces of the tip and crown of the softened blank in a mold of desired shape, positioning the braid convolutions by manipulating the same from the inside of the hat while gauging the desired position by the stitching exposed on the 10 inside of the hat, and thereafter applying pressure to the inner surface of the hat blank to mold the same to the desired shape.

OSCAR WIEDEMAN. 15
